UNITED STATES PATENT OFFICE.

JACOB A. STEPHENSON, OF CLEMENTS, KANSAS.

TOOL-HANDLE BRACE.

1,295,628.

Specification of Letters Patent.

Patented Feb. 25, 1919.

Application filed October 16, 1915. Serial No. 56,288.

To all whom it may concern:

Be it known that I, JACOB A. STEPHENSON, a citizen of the United States, residing at Clements, in the county of Chase and State of Kansas, have invented certain new and useful Improvements in Tool-Handle Braces; and I do hereby declare the following to be a full, clear, and exact description of the invention, such as will enable others skilled in the art to which it appertains to make and use the same.

This invention relates to tools, such as hammers, hatchets, picks, axes or the like, and more particularly to a brace to be used in connection with the handles or helves of the various tools, which provides a brace for the handle, and also means for preventing the tool from flying off the end of the handle.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:—

Figure 1 is a side elevation of a tool having the improved braces attached thereto, and showing parts of the tool and handle or helve in section,

Fig. 2 is a perspective view of the brace, and

Fig. 3 is a side elevation of a different type of tool to that illustrated in Fig. 1.

Referring more particularly to the drawings, 1 designates the tool head, which in Fig. 1, is shown as an ordinary claw hammer. The hammer head 1 is provided with the usual form of eye 2, and also with angular recesses 3 formed therein and communicating with the eye 2 of the hammer head.

The handle or helve 5 of the hammer illustrated in Fig. 1, is provided with a pair of longitudinally extending recesses or slots 6 and 7, which extend inwardly from the end of the handle upon which the hammer head 1 is mounted. The improved braces, indicated by the numeral 8, are seated in the recesses 6 and 7, upon opposite sides of the handle and are held therein by a rivet 9 which extends through their rear

or inner end, and through the handle 5. The brace rods 8 are constructed of any suitable type of metal, and positioned diametrically opposite of each other upon the handle 5, extending through the eye 2 of the hammer head 1. Angular lugs 10 are formed upon the members or brace rods 8 and are provided for seating in the recesses 3 and 4, for preventing the accidental dislodgement or disconnection between the hammer head and handle or helve 5. The rods or braces 8 protect the handle 5 and materially decrease the liability of breaking the handle, owing to the fact that a large majority of handles of tools of this nature are broken close to the heads or tools which are mounted thereon.

In Fig. 3 of the drawings, a different type of tool is shown, which is the ordinary type of excavating pick, including the pick head 20 having the picking point 21 formed thereon, as is ordinary in the construction of tools of this nature. The hub section 22 of the pick head 20 is provided with an eye 23 having angular recesses 24 communicating therewith, which are provided for receiving the angular lugs 25 formed upon the braces or rods 26. The rods or braces 26 are seated in recesses 27 formed in the handle 28 of the pick, in the same manner in which the braces or rods 8 are attached to the hammer handle 5.

From the foregoing description taken in connection with the accompanying drawings, it will be seen that a brace is provided for attachment to the handles of various types of tools, such as hammers, axes, picks, sledge hammers or the like, which will perform the dual function of bracing the handle and materially decreasing the liability of the splitting or breaking of the same, and also prevent the tool head from flying off or being accidentally removed from connection with the handle or helve of the tool.

In reducing the invention to practice, certain minor features of construction, combination and arrangement of parts may necessitate alterations to which the patentee is entitled, provided such alterations are comprehended within the scope of what is claimed.

What is claimed is:—

In a tool handle fastener, the combination of a tool head having an eye extending therethrough and provided in a pair of its

opposed walls with angular recesses communicating with the eye, a handle having its outer end located in said eye, said handle being provided with a pair of longitudinally 5 extending and diametrically opposed recesses opening at their outer ends through the outer end of the handle and terminating at their inner ends in shoulders, the wall of each recess presenting a substantially flat 10 smooth surface, substantially flat elongated bracing plates seated in said handle recesses and lying flush with said handle, the inner ends of said plates engaging said shoulders to prevent rearward movement thereof with 15 relation to the handle and forward move-

ment of the handle with relation to the plates, angular lugs formed upon and projecting outwardly from said plates adjacent one end thereof and snugly fitting in said angular recesses to prevent said head from having any forward or rearward movement with relation to the handle, and a rivet extending through said plates and handle. 20

In testimony whereof I affix my signature in presence of two witnesses.

JACOB A. STEPHENSON.

Witnesses:

EARL JAMES,
JOHN A. CRAWFORD.
